UNITED STATES PATENT OFFICE.

WILLIAM H. ROSE, OF JERSEY CITY, NEW JERSEY.

CONTAINER COVER.

Application filed December 26, 1925. Serial No. 77,744.

My invention relates to container covers and processes for producing the same and refers particularly to covers capable of hermetically sealing containers and which are so constructed as to be readily opened and processes for producing the same.

The object of my invention is a metallic container cover capable of being readily attached to a container, and so constructed that its plurality of hermetically sealed members may be readily separated when it is desirous of obtaining access to the container contents.

Container covers of the character described, and especially those adapted for use with preserved food products, must be absolutely air-tight even under considerable outward pressure, and must be capable of being readily opened when desired. They should also be economic in construction in both process of production and amount of material employed.

The device of my invention possesses all of these desirable properties and presents an economic and efficient and hermetically sealed cover for containers.

My device comprises a flanged central member and an outer member having an opening of less diameter than the diameter of the central member, the flange being folded into an S-shape with the peripheral portions of the outer member opening being within the curves of the S-shaped flange.

The several steps of production of my device, and the device itself, are fully explained in this specification with its accompanying drawings which will indicate the novelty, usefulness and effectiveness of my device.

In the accompanying drawings illustrating my invention, similar parts are designated by similar numerals.

Figure 1 is a top plan view of one form of my device.

Figures 2, 3, 4, 5, 6 and 7 are vertical cross-sections illustrating successive steps in the production of the device of Figure 1, Figure 7 showing the completed device attached to a can or container.

The particular form of the device of my invention shown in the accompanying drawings comprises two removably attached members 10 and 11. The central member 10 has a downwardly extended flange 12 around its

periphery. The outer member 11 has an opening 13, of the same shape as the member 10 but of less diameter than the diameter of the latter.

The formation of the completed cover is as follows:—The flange 12 of the member 10 is spun inwardly as shown in Figure 3. The member 10 is then positioned within the opening 13 of the member 11 as shown in Figure 4. The portion of the flange 12 below the member 11 is then spun outwardly as shown in Figure 5 to form a recess in which the inner portion of the member 11 is positioned. The portion of the flange 12 above the member 11 is then spun outwardly as shown in Figure 6 and the jointure between the flange 12 and the member 11 is made complete by pressing the two curved positions of the flange 12 into close abutment with the member 11. The operation shown in Figure 6 may sometimes be omitted and the complete closure between the flange 12 and the member 11 accomplished by the operation shown in Figure 7, or the two spinning operations of the flange 12 shown in Figures 5 and 6 may be performed simultaneously.

It is advisable that a proper cementitious material 14 be placed upon both sides of the member 11, in order to assist in the production of a hermetical jointure between the flange 12 and the member 11.

The cover can then be permanently attached to a can, or receptacle, 15, by any proper means.

In order to open the cover, thus formed, a pointed flat instrument, as a screw driver, chisel, or other suitable device 16 is forcibly inserted between the flange 12 and the member 11 and used as a lever for displacing the sealing members, allowing of the removal of the central member 10.

Another suggested means of opening the cover is to spot weld a ring 17 to the member 10 near its periphery, the ring 17 carrying a second ring 18, an upward pull upon which will disengage the sealing members.

From the above, it will be noted, that the periphery of the opening of the outer member 11 is tightly wedged within the S-shaped flange 12 of the central member 10.

I do not limit myself to the particular size, shape, number, or arrangement or material of parts, nor to the particular steps of

procedure shown and described as these are given simply as a means for clearly describing my invention.

What I claim is:—

- 5 1. In a container cover device capable of attachment to the sides of a container, in combination, a side member capable of attachment to the sides of a container and having an opening therein; and a removable cover of greater diameter than the side member opening, the outer edge of which is bent downwardly, inwardly, downwardly and outwardly forming an S-shaped member, the cover being positioned externally of a container to which the device is attached, the aperture defining edge of the side member being positioned within and hermetically sealed to the S-shaped member and the S-shaped member being so positioned with respect to a jointure between the side member and a container side, that a lever placed within the S-shaped member will fulcrum upon the jointure for the outward removal of the cover by means of force applied thereto.
- 10 2. In a container cover device capable of attachment to the sides of a container, in combination, a side member capable of attachment to the sides of a container and hav-
- 15
- 20

ing an opening therein; a removable cover of greater diameter than the side member opening, the outer edge of which is bent 25 downwardly, inwardly, downwardly and outwardly forming an S-shaped member, the cover being positioned externally of a container to which the device is attached, the aperture defining edge of the side member 30 being positioned within and hermetically sealed to the S-shaped member and the S-shaped member being so positioned with respect to a jointure between the side member and a container side, that a lever placed 35 within the S-shaped member will fulcrum upon the jointure for the outward removal of the cover by means of force applied thereto.

Signed at New York city in the county of 40 New York and State of New York this 21st day of December, 1925.

WILLIAM H. ROSE.
